W.M. Cutler and BY
ATTORNEY

UNITED STATES PATENT OFFICE

CHARLES B. SHEPHERD, OF NEW YORK, N. Y., ASSIGNOR TO THE P & M COMPANY, OF CHICAGO, ILLINOIS, A CORPORATION OF ILLINOIS

RAIL ANCHOR

Application filed May 9, 1928. Serial No. 276,207.

This invention relates to rail anchors and has for an object to provide a rail anchor which is simple and economical to manufacture and when applied in position on a rail base flange it will tenaciously grip and effectively hold the rail base flange from longitudinal creeping. 5

A further object of this invention is to provide a rail anchor having a jaw-like member provided with a vertical depending loop.

Further objects will appear from the following description, appended claims and the accompanying drawings in which—

Figure 1 is an isometric view of the rail anchor constituting my invention. 15

Figure 2 shows the anchor applied to a rail base flange, the rail being shown in section.

Figure 3 illustrates one of the positions 20 assumed by the anchor when being applied to a rail base flange.

Figure 4 illustrates the relation of parts prior to the application of the anchor (in full lines) and the relation and distortion 25 of parts when the anchor has been applied (in dotted lines).

Referring to the drawings in which there is illustrated one modification of my invention and in which like reference numerals 30 designate like parts, the reference numeral 1 designates a body member or arm which is adapted to extend transversely to and beneath the rail base flange. Disposed at one end is a rail flange-engaging means 2. The 35 rail flange-engaging means 2 comprises a vertically depending looped member functioning as a tie-abutting means and having normally spaced apart legs 3 and 4. If desired, the lower portion of the looped member may 40 be formed to lie in a plane other than that occupied by the remaining parts of the anchor. In other words, the lower portion of the looped member may be offset relatively to the body member. The leg 3 which, as is 45 illustrated in the drawing, is of a greater length than the leg 4 and, due to the easy bend at its lower extremity, is adapted to yieldingly engage the vertical edge of the rail base flange with its inner surface 5. The 50 leg 3 terminates at its upper end in a sub-

stantially rigid member 6 which is adapted to engage the upper surface of the rail base flange. This member may be made of any shape or contour. I prefer, however, to make it of the same shape as the rail base flange 55 which it is intended to engage.

Disposed beneath the member 6 and on the shorter leg 4 is a resilient member 7 which is adapted to engage the under surface of the rail base flange. These two members 6 and 7 are spaced from each other a distance less than the thickness of the rail base flange which they are intended to embrace. On the opposite end of the body member 1, there is a rail base flange-engaging means 8. This 65 rail flange-engaging means 8 may be of any well-known kind. I prefer, however, to make it in the form of an upstanding lip 9 which is intended to engage the vertical edge 70 of the rail base flange. In its normal or rest 70 position, the distance between the vertical edge 5 and the lip 9 is less than the width of a standard rail base flange. This structure enables the anchor to exert a pressure transversely of the anchor when in position 75 thereon.

The holding grip and thrusts on the rail base flange are increased by normally disposing the yielding member 7 in a plane higher than that occupied by the central portion of 80 the body member 1 and forming a small portion 10 of the body member 1 adjacent the lip 9 to occupy, when the anchor is free of the rail, a plane higher than that in which the yielding member 7 lies, whereby the portion 10 is forced downwardly relative to the member 7 when the anchor is in its applied position. 85

To apply the anchor to a rail base flange, the jaw member 2 is pushed on a rail base 90 flange as far as it will easily go. At the end of this operation the anchor assumes the position illustrated in Figure 3. The vertical leg 3 is then struck on its upper surface 11 with a spike maul or sledge whereby, due to 95 the construction of the anchor, various parts thereof are distorted. The arm or body member 1 is elongated, the jaw members 6 and 7 are spread apart and the leg 3 moved outwardly as shown in Figure 4. The elong- 100

gation of the anchor occasioned by the elongation of the body member 1 and the outward movement of the leg 3 permit the lip 9 to clear the opposite edge of the rail base flange and snap into position.

5 The relation of parts before and after application of the anchor is clearly disclosed in Figure 4. When applied in place, the anchor exerts a powerful transverse pressure by means of the vertical edge 5 and the lip 9. An upward pressure is exerted by the resilient jaw member 7 and the portion 10 adjacent the lip 9. The substantially rigid member or jaw member 6 exerts a downward pressure. It is thus seen that the anchor securely and tenaciously holds and grips the rail base flange and prevents longitudinal creeping of the rails.

20 Since it is obvious that modifications may be made without departing from the nature of the invention, I do not intend to limit myself to the exact details above described except as set forth in the claims.

I claim:

25 1. A rail anchor comprising a body member, a downwardly depending looped member disposed at one end thereof, said looped member having legs of unequal length, means adapted to engage the upper surface of the rail base flange disposed on the longer leg, and means disposed on the shorter leg adapted to engage the under surface of said rail base flange at a location spaced inwardly from the edge surface of said flange and 30 rail base flange-engaging means disposed on the opposite end of said body member.

40 2. A rail anchor comprising a body member, a downwardly depending looped member disposed at one end thereof, said looped member having legs of unequal length, means adapted to engage the upper surface of the rail base flange disposed on the longer leg, and yielding means disposed on the shorter leg adapted to engage the under surface of said rail base flange at a location spaced inwardly from the adjacent edge of the rail base, and rail base flange-engaging means disposed on the opposite end of said body member.

45 3. A rail anchor comprising a body member, a vertically disposed looped member at one end thereof and in the vertical plane of the body, said looped member having a long leg and a short leg, said short leg positioned forward of said long leg, said long leg adapted to bear again the vertical edge only of a rail base flange, means adapted to engage the upper surface of said rail base flange disposed on one end of said long leg, means 55 adapted to engage the under surface of said rail base flange disposed on said short leg, and rail flange-engaging means disposed on the opposite end of said body member.

60 4. A rail anchor comprising a body member, a looped member disposed at one end

thereof, said looped member having a long vertical leg and a short vertical leg, said short leg positioned forward of said long leg, said long leg adapted to engage the vertical edge of a rail base flange, means adapted to engage the upper surface of said rail base flange disposed on one end of said long leg, yielding means disposed on said short leg adapted to engage the under surface of said rail base flange at a point spaced inwardly from the edge surface thereof, and rail flange-engaging means disposed on the opposite end of said body member.

65 5. A rail anchor comprising a bowed body member, a looped member disposed at one end thereof, said looped member having a long vertical leg and a short vertical leg, said short leg positioned forward of said long leg, said long leg being yieldable transversely of the rail and adapted to engage the vertical edge of a rail base flange, means adapted to engage the upper surface of said rail base flange disposed on one end of said long leg, means 70 adapted to engage the under surface of said rail base flange disposed on said short leg, and rail flange-engaging means disposed on the opposite end of said body member.

75 6. A rail anchor comprising a bowed body member, a looped member disposed at one end thereof, said looped member having a long vertical leg and a short vertical leg, said short leg positioned forward of said long leg, said long leg being yieldable and adapted to engage the vertical edge of a rail base flange, means adapted to engage the upper surface of said rail base flange disposed on one end of said long leg, yielding means on said short leg adapted to engage the under surface of said rail base flange at a point intermediate the edge of said flange and the inner extremity of said upper bearing means, and rail flange-engaging means disposed on the opposite end of said body member.

80 7. A rail anchor comprising an arm portion which extends transversely beneath the rail base and formed at one end with a shoulder for engagement with the edge surface of one base flange of the rail and formed at the other end with a bend providing a resilient bearing for engagement with the bottom of the base at a location spaced inwardly from the edge surface of the other base flange, means for bearing against the top surface of the last mentioned flange, and a vertical loop connecting said top and bottom bearings; the space between said top and bottom bearings being normally less than the thickness of the base flange engaged, whereby said loop is strained by movement of the anchor to its applied position.

85 8. A rail anchor comprising an arm portion which extends transversely beneath the rail base and formed at one end with a shoulder for engagement with the edge surface of one base flange of the rail and formed at

the other end with a bend providing a resilient bearing for engagement with the bottom of the base at a location spaced inwardly from the edge surface of the other base flange, 5 means for bearing on the top surface of the last mentioned flange, and a vertical loop connecting said top and bottom bearings, one leg of which loop bearing against the edge surface of the last mentioned flange; the 10 space between said top and bottom bearings being normally less than the thickness of the base flange engaged and the distance between the said leg of said loop and said shoulder being normally less than the width 15 of the rail base, whereby said loop is strained both vertically of and transversely of the rail by movement of the anchor to its applied position.

In testimony whereof, I have affixed my
signature to this specification.

CHARLES B. SHEPHERD.
